UNITED STATES PATENT OFFICE.

JOHN A. DE MOND, OF RICHMOND, CALIFORNIA.

EXPANSION-JOINT FOR CONCRETE CONSTRUCTIONS.

1,239,578.

Specification of Letters Patent. Patented Sept. 11, 1917.

Application filed June 2, 1916. Serial No. 101,306.

To all whom it may concern:

Be it known that I, JOHN A. DE MOND, a citizen of the United States, residing at Richmond, in the county of Contra Costa 5 and State of California, have invented certain new and useful Improvements in Expansion-Joints for Concrete Constructions; and I do hereby declare the following to be a full, clear, and exact description of the invention, such as will enable others skilled in the art to which it appertains to make and use the same.

The primary object of this invention is the provision of a novel type of expansion 15 joint for use in concrete construction, particularly a pavement, which will admit of adjacent blocks being laid in close relation to each other so as to lessen the space between the blocks.

Another object of the invention is the provision of an expansion joint, which will prohibit the growth of vegetation, such as 20 weeds and grass, between the adjacent blocks.

A further object of the invention is the provision of an expansion joint formed of 25 companion sheets of tarboard, or similar flexible material, having a filler therebetween, the said filler being composed of asphaltum and rock salt, and means associated with the sheets for preventing escape 30 of the filler from between the sheets.

A still further object of the invention is the provision of an expansion joint, for carrying out the above object, which can be 35 conveniently and expeditiously placed in operative position, and will be of simple and durable construction, cheap to manufacture and efficient in operation.

Other objects will appear and be better 40 understood from that embodiment of my invention of which the following is a specification, reference being had to the accompanying drawing forming a part thereof, in which:

Figure 1 is a top plan view of a concrete construction undergoing completion, showing the improved expansion joint in operative position,

Fig. 2 is a vertical section, taken through 50 a completed concrete structure, and showing the expansion joint in operative position.

Fig. 3 is a perspective view of the expansion joint removed from operative position.

Referring to the drawing in detail, the 55 letter A designates a concrete construction, which for conventional purposes is shown

as a pavement, and being formed of individual blocks designated B and C. In Fig. 1 the block B is shown complete, and the block C undergoing the usual molding operation and partly completed.

The expansion joint is designated, as an entirety, by the numeral 1 and consists of companion sheets of tarboard or the like, designated 2 and 3, the said sheets being equal in length and width. The sheet 3 is provided with a horizontally disposed bulged portion 4, which is located at a point adjacent the upper edge of the sheet 3, and a filler 5 is interposed between the sheets 2 and 3 and is formed of a compound containing asphaltum and rock salt, which, will admit of a relative movement of the sheets 2 and 3 during the expansion and contraction of the adjacent blocks. As rock salt is one of the constituents of the filler, the same will prevent the growth of vegetation between the sheets and the blocks. During the molding of the block B, the bulged portion 4 becomes embedded in the block and serves as an anchor, and, as shown in Fig. 2, the bulged portion 4 contains a large portion of the filler 5, so as to admit of the bulged portion having sufficient rigidity and also to admit of the wall thereof expanding and contracting with the material forming the block B.

The lower ends of the sheets 2 and 3 are bent and extended at right angles to the blocks, as shown at 6 and 7, and the plastic material, of which the blocks are formed, is poured on the extensions 6 and 7 so as to embed the extensions within the material, the said extensions serving to securely hold the sheets to the adjacent blocks and also to prevent the growth of vegetation between the adjacent blocks.

The adjacent upper edges of the sheets 2 and 3 are folded and a binding element 8 extends around the edges of the sheets and serves to prevent the escape of the filler from between the sheets.

In laying adjacent blocks, the expansion joint is placed at the required point with the extensions 6 and 7 lying on the ground or other surface. A board 9, shown in Fig. 1, is positioned against the sheet 2 so as to render the joint rigid during the molding of the blocks. The plastic material is poured, in the usual manner, on the opposite sides of the joint and on the extensions 6 and 7, the plastic material forming the

block B contacting with the sheet 3 so as to admit of the forward portion 4 being embedded within the material. The plastic material forming the block C is held away 5 from the sheet 2, by the board 9, and after the material has been molded into block formation, and before the material has set, the board 9 is removed so as to admit of the plastic material moving against the sheet 2, 10 as shown in Fig. 2, to close the space between the sheet 2 and the block C.

Having thus described the invention what is claimed as new, is:

1. An expansion joint for concrete construction consisting of a pair of compressible sheets, one of the sheets having a bulged portion therein, and a filler within the bulged portion and formed of asphaltum and rock salt.

2. An expansion joint for concrete construction consisting of a pair of compressible sheets, one of the sheets having a bulged portion therein, and a filler within the bulged portion.

3. An expansion joint for concrete construction consisting of companion sheets of flexible material, a filler interposed between the sheets, and a binding element extending around the adjacent edges of the sheets to secure the sheets together and prevent the escape of the filler from between the sheets.

In testimony whereof I affix my signature in presence of two witnesses.

JOHN A. DE MOND.
